(57) **CLAIM**

The ornamental design for an infrared microscope, as shown and described.

DESCRIPTION

FIG. 1 is a perspective view of an infrared microscope showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof;

FIG. 9 is a cross-section view thereof, taken along the line 9-9 of FIG. 3;

FIG. 10 is a cross-section view thereof, taken along the line 10-10 of FIG. 3; and,

FIG. 11 is a cross-section view thereof, taken along the line 11-11 of FIG. 3.

The broken lines depict portions of the infrared microscope and form no part of the claimed design.

1 Claim, 11 Drawing Sheets
